SHEET GRIPPING DEVICE

Frank R. Belluche, Racine, Wis., assignor to
 Christensen Machine Company, Racine, Wis.,
 a corporation of Wisconsin

Application April 23, 1934, Serial No. 721,921

24 Claims. (Cl. 271—79)

This invention relates to sheet grippers for printing machines and refers more particularly to what is known in the printing art as a gripper bar. Devices of this character generally form part of a movable conveyer to carry sheets from one location to another and comprise a cross bar on which a plurality of individual grippers are mounted to be simultaneously closed and opened.

It is an object of this invention to provide a gripper bar of the character described, which is of compact construction with its weight centered closely about the axis of the bar to thereby diminish the "throwing" effect of centrifugal force as the bar is carried around turns.

Another object of this invention is to provide an improved construction for gripper bars wherein the means for opening the individual grippers is located within the supporting bar as distinguished from past constructions in which the gripper opening means is located entirely outside the supporting bar.

And a further object of this invention is to generally improve and simplify the construction of gripper bars of this character.

With the above and other objects in view which will appear as the description proceeds, my invention resides in the novel construction, combination and arrangement of parts substantially as hereinafter described and more particularly defined in the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a side view of a gripper bar embodying this invention, the central portion thereof being broken away;

Figure 2 is an enlarged end view taken on the plane of the line 2—2 in Figure 1, and illustrating the manner in which the bar is attached to a conveyer chain;

Figure 3 is a top view taken on the plane of the line 3—3 of Figure 2, with portions broken away and in section showing the detailed construction at one end of the bar;

Figure 4 is a cross section view taken through Figure 3 on the plane of the line 4—4;

Figure 5 is a cross section view taken through Figure 1 on the plane of the line 5—5;

Figure 6 is a detail section view taken through Figure 5 on the plane of the line 6—6; and
 Figure 7 is a detail section view taken through Figure 1 on the plane of the line 7—7.

Referring now more particularly to the accompanying drawings, in which like numerals indicate like parts throughout the several views, the numeral 5 designates the outer supporting tube of the bar upon which the grippers 6 are mounted and within which a gripper actuating tube 7 is disposed. At its ends the tube 5 has bushings 8 (see Figure 3), which provide bearings to rotatably mount the gripper actuating tube 7.

Fixed to the ends of the outer supporting tube 5 are coupling members or supporting brackets 9 and 10, by which the bar is attached to a pair of endless conveyer chains 11, indicated in construction lines in Figures 2 and 3.

The chains 11 support the entire structure and carry the same along the desired path of movement, and as the chains are often of necessity trained about small diameter sprockets, it is essential that the weight of the gripper bars be closely centered about the axis of the bar to preclude excessive "throwing" resulting from the effect of centrifugal force.

In past constructions, this was not easily accomplished in view of the fact that the gripper actuating mechanism was always mounted exteriorly of the supporting bar, but in the present invention, this objection is entirely overcome by the novel telescoped construction employed.

The end coupling members or supporting brackets 9 and 10 are clamped to the ends of the outer tubes 5 by having their attaching hubs 12 split and provided with clamping screws 13. Both end members 9 and 10, have end walls 14 at their extreme outer ends provided with spaced holes to receive attaching pins 15 by which the gripper bar is connected to the conveyer chains 11.

At the end of the structure at which the supporting bracket 9 is located, the inner tube 7 has a lever 16 clamped thereto. A short hub 17 extends from the lever 16 into the end of the outer supporting tube 5 to engage the adjacent end of the bearing bushing 8 and thereby limit relative axial or longitudinal movement between the inner tube and outer tubes in one direction. Endwise shifting in the opposite direction is restrained by a collar 18 clamped to the opposite end of the inner tube 7 and likewise provided with a hub which projects into the adjacent end of the outer tube to engage the adjacent bearing bushing 8.

The lever 16 carries a roller 19 at its outer free end.

end to track on a cam 20 indicated in construction lines in Figure 4, which is fixedly mounted at the point in the path of movement of the gripper bars at which opening of the grippers is desired.

In riding over the cam 20, the roller 19, through its mounting lever 16, imparts a degree of counter-clockwise rotation to the inner tube 7 as viewed in Figure 4. This counter-clockwise rotation on the part of the inner tube, with respect to the outer tube is utilized to open the grippers 6.

The specific construction of the grippers is best illustrated in Figure 5. As here shown, each gripper comprises stationary and movable jaws 23 and 24 respectively. The stationary jaw 23 is formed by one end of a flat metal strip 25 partially encircling the outer supporting tube 5 and secured thereto by screws 26.

At both ends, the strip 25 is reduced in width and one end is bent back on itself to provide the stationary jaw 23 and its other end is curled back to provide a bearing 27 for a hinge pin 28, which mounts the movable jaw 24.

The movable jaw 24 is preferably stamped from sheet metal and comprises a curved arm 29, the outer end of which provides the jaw 24 and the inner end of which has two parallel arms 30 extending inwardly therefrom to overlie the ends of the bearing 27 and project through openings 31 and 32 in the outer supporting tube 5 and the inner actuating tube 7, respectively. The hinge pin 28 has its ends passing through the arms 30 to thereby hingeably mount the movable jaw as will be readily apparent.

The movable jaw of the gripper is yieldably urged to its closed sheet gripping position by a spring 33 confined between a short rearward extension 34 on the arm 29 and the adjacent portion of the strip 25, which carries a lug 35 to engage the spring end. Each gripper is thus independently closed.

The extreme end of the parallel arms 30, which project into the openings 32 in the inner actuating tube 7 carry a roller 36 with which the side edge 37 of the opening 32 engages upon counter-clockwise rotation of the actuating tube effected by the roller 19 riding up on the cam 20, as hereinbefore described, to swing the arm 29 about its hinged mounting 28. In this manner all of the grippers are simultaneously opened.

To insure complete closure of the grippers by their individual springs 33, the inner actuating tube 7 is yieldably urged to a position of clockwise rotation at which the edges 37 of its several openings 32 are spaced from the rollers 36 on the actuating arms of the grippers. This function is attained by a compression spring 39 located at the end of the gripper bar at which the coupling member or bracket 10 is mounted.

The spring 39 is coiled about a pin 40, which is adjustably threaded as at 41 in a boss 42 on the member 10. The opposite end of the pin 40 passes freely through an opening 43 in a lug or arm 44 carried by and extending endwise from the collar 18, so that the spring 39 is confined between the arm or lug 44 and the boss 42 on the member 10.

To limit the movement of the collar 18 and consequently the tube 7 in response to the action of the spring 39, a head 45 is provided on the outer end of the pin against which the lug or arm 44 abuts. The limit of movement thus defined is adjustable by threading the pin into and out of the opening 41, a lock nut 47 being provided to secure the pin in adjusted position.

If desired, the grippers may be provided with individual stops 48 to stop and straighten the sheets S as they are fed to the grippers. These stops have a bifurcated end 49 to straddle the jaws 23 and 24 and are conveniently held in place by the screws 26, which secure the stationary jaws to the supporting bar.

From the foregoing description taken in connection with the accompanying drawings, it will be readily apparent to those skilled in the art to which this invention appertains, that a novel and improved gripper bar construction has been provided in which the objectionable effects of centrifugal force are reduced to a minimum by locating the gripper actuating means within a hollow supporting bar.

What I claim as my invention is:

1. A sheet gripping device of the character described comprising, a plurality of telescoped relatively rotatable tubes, complementary hingedly connected movable and stationary gripping jaws forming a loop about said tubes, detachable means for securing the stationary jaw to the outer tube to detachably mount the assembled gripping jaws on the outer tube and means to open the jaws upon relative rotation of said tubes.

2. A sheet gripping device of the character described comprising, a tubular supporting member, sheet gripping means including a movable gripper jaw, means substantially embracing the tubular supporting member and detachably secured thereto for mounting the gripping means on said supporting member, means to yieldably urge the movable gripper jaw to its closed sheet gripping position, and means within the tubular supporting member to move the movable gripper jaw to its open sheet releasing position.

3. A sheet gripping device of the character described comprising, a tubular support, a movable gripper jaw hingedly mounted on the exterior of the support, a part fixed to the movable gripper to swing about the axis of the hinged mounting for the movable gripper and extending into the tubular support, and an actuating member within the tubular support engageable with said part to actuate the gripper jaw.

4. A sheet gripping device of the character described comprising, a tubular support, a movable gripper jaw hingedly mounted on the exterior of said support and having a part projecting into the interior thereof, means to yieldably urge the jaw to its closed sheet gripping position, and an actuating member rotatable within the tubular support and engaging said part of the gripper jaw to move the same against the action of its yieldable urging means to open sheet releasing position.

5. A sheet gripping device of the character described comprising, a tubular supporting member, an actuating member rotatably mounted within the tubular supporting member, a plurality of movable gripper jaws hingedly mounted on the exterior of the supporting tube with parts projecting through openings in the tube for engagement with the actuating member therein, and means to turn the actuating member to simultaneously move all of the gripper jaws.

6. A sheet gripping device of the character described comprising, a tubular supporting member, complementary hingedly connected stationary and movable gripping jaws, said jaws together forming a loop encircling the supporting member, the stationary jaw having a portion in contact with the exterior of the supporting mem-

ber, securing means fixing said portion of the stationary jaw to the support so as to mount the assembled complementary jaws on the support, the movable jaw having a part projecting into the interior of the tubular support, and means within the tubular support and engageable with said part for moving the movable jaw.

7. A sheet gripping device of the character described comprising, a supporting tube, hingedly connected stationary and movable gripping jaws forming a loop about the tube and mounted on the exterior thereof, the movable jaw having a part projecting through an opening in the tube into the interior thereof, a spring to yieldably urge the jaws to closed position, and a rotatable actuating tube within the supporting tube and connected with said part of the movable jaw for opening the jaws.

8. A gripper bar of the character described comprising, a supporting tube, means at the end of the tube to attach the same to conveyer chains, an actuating member rotatably mounted within the tube, means carried by the actuating member for imparting rotation thereto with respect to the supporting tube, and complementary stationary and movable gripper jaws carried by the supporting tube, the movable gripper jaws having parts projecting into the interior of the supporting tube and engaging the actuating member to be movable upon rotation of said actuating member.

9. A gripper bar comprising, a supporting tube, means at the ends of the bar for attaching the same to conveyer chains, an actuating member within the supporting tube, bearings to rotatably mount the actuating member for relative rotation with respect to the tube about the axis of the tube, means connected with the actuating member to yieldably urge the same to a predetermined position of rotation with respect to the tube, means connected with the actuating member and engageable with a cam to turn the actuating member against the action of its yieldable urging means, and complementary stationary and movable gripper jaws carried by the supporting tube, the movable jaws having parts projecting through openings in the supporting tube for engagement with the actuating member, whereby rotation of the actuating member actuates the movable jaws.

10. In a sheet gripping device of the character described, a supporting tube, an actuating tube telescoped within the supporting tube and rotatable with respect thereto, said tubes having openings opposite each other, a movable gripper jaw on the exterior of the supporting tube, mounting means for the gripper jaw fixed to the outside of the supporting tube, means hingedly connecting the gripper jaw with said mounting means, a part carried by the gripper jaw and projecting through the opening in the supporting tube and extending into the opening in the actuating tube, whereby rotation of the actuating tube moves the gripper jaw, and means to move the actuating tube with respect to the supporting tube.

11. In a sheet gripping device of the character described, a supporting bar, complementary stationary and movable gripper jaws carried by the supporting bar, the stationary jaw being of arcuate shape with its inside diameter such that the stationary jaw fits the outside diameter of the tubular supporting bar and partially encircles the supporting bar, means for detachably securing the stationary jaw to the supporting bar, said stationary jaw having a portion formed to pro-

vide a sheet engaging surface, means to hingedly connect the movable jaw to the stationary jaw for swinging movement to and from engagement with the sheet engaging portion of the stationary jaw, and yieldable means carried by the complementary jaws to urge the movable jaw to its closed sheet gripping position.

12. In a sheet gripping device of the character described, a tubular supporting bar, complementary stationary and movable gripper jaws carried by the tubular supporting bar, the stationary jaw being of arcuate shape with its inside diameter such that the stationary jaw fits the outside diameter of the tubular supporting bar and partially encircles the tubular supporting bar, means for detachably securing the stationary jaw to the supporting bar, said stationary jaw having a portion formed to provide a sheet engaging surface, means to hingedly connect the movable jaw to the stationary jaw for swinging movement to and from engagement with the sheet engaging portion of the stationary jaw, yieldable means carried by the complementary jaws to urge the movable jaw to its closed sheet gripping position, and means within the tubular supporting bar for swinging the movable jaw about its hinged connection with the stationary jaw to an open sheet releasing position.

13. In a sheet gripping device of the character described, a supporting tube, an actuating member rotatable within the supporting tube about the axis of the tube, stop means secured to the ends of the actuating member to hold the same against endwise shifting with respect to the supporting tube, coupling members secured to the ends of the supporting tube for connecting the tube to conveyer chains, means carried by one of the stop means and the adjacent coupling member for yieldably urging the actuating member to a predetermined position of rotation with respect to the supporting tube, a cam follower carried by the other of said stop means and engageable with a stationary cam upon passage of the device therewith to impart rotation to the actuating member against the action of said yieldable means, and movable gripper jaws carried by the supporting tube and having parts projecting into the interior thereof for engagement with the actuating member to be operable thereby upon rotation thereof.

14. In a sheet gripping device, a supporting bar, a stationary gripper jaw fixed to the supporting bar and having a sheet engaging portion spaced from the supporting bar, a movable jaw hingedly connected to the stationary jaw and forming therewith a loop encircling the supporting bar with its free end portion engageable with said sheet engaging portion, and means adjacent the sheet engaging portions of the jaws to provide a stop to straighten the sheet preparatory to being gripped by said jaws.

15. In a sheet gripping device of the character described, a supporting bar, hingedly connected complementary movable and stationary jaws forming a loop encircling the supporting bar, means for detachably securing the assembled jaws to the supporting bar, and stop means held in place on the supporting bar by the same securing means and having a portion adjacent the sheet engaging parts of the jaws against which a sheet is brought to bear to definitely locate the sheet with respect to the jaws and the carrier bar.

16. A sheet gripping device for use with printing machines and the like comprising a supporting tube, means at the ends of the tube for con-

necting the same with conveyer chains, complementary hingedly connected stationary and movable jaws forming a loop about the supporting tube, means for readily detachably securing the 5 fixed jaw to the supporting tube, an arm carried by the movable jaw and projecting through an opening in the supporting tube into the interior thereof, and an actuating member rotatable within the supporting tube and readily detachably connected with said arm for actuating the movable gripper.

17. A sheet gripping device for printing machines and the like comprising a supporting tube, means at the ends of the tube for connecting the 15 same with conveyer chains, an arcuate band embracing the supporting tube and having one end portion bent to form a sheet engaging part, means for detachably securing said band to the tube, a movable jaw hingedly connected to said band with its free end portion arranged to engage said 20 sheet engaging part, an arm carried by the movable jaw and extending through an opening in the tube into the interior thereof, and means within the tube connected with said arm for actuating the movable jaw.

18. A sheet gripping and conveying device for use with printing machines and the like comprising a supporting tube, means at the ends of the tube for connecting the same with conveyer 30 chains, a fixed jaw in the form of a metal band embracing the tube and having one end portion thereof bent to provide a sheet engaging surface spaced from the exterior of the tube, means for detachably securing the fixed jaw to the tube, a movable jaw hingedly connected to the fixed jaw 35 and supported thereby with its free end portion engageable with the sheet engaging portion of the fixed jaw, spring means to hold the jaws closed, and means for opening the jaws.

40 19. As an article of manufacture, a pair of complementary sheet gripping jaws attachable to a supporting bar and comprising a stationary jaw in the form of a substantially arcuate metal band adapted to embrace and be secured to the supporting bar, one end portion of said band being shaped to provide a sheet engaging surface, and a movable jaw one end of which is engageable with the sheet engaging portion of the fixed jaw, a pair of parallel spaced arms carried by the opposite end portion of the movable jaw straddling the opposite end of said band, a hinge pin connecting said arms and said end portion of the band, and spring means for yieldingly holding the jaws closed.

55 20. In a sheet gripping device of the character described, a supporting bar, hingedly connected complementary movable and stationary jaws forming a loop encircling the supporting bar, the stationary jaw being in direct engagement with the supporting bar and having a sheet engaging portion spaced from the outside of the supporting bar, means for detachably securing said portion of the fixed jaw to the supporting bar, the movable jaw having a free end portion engageable with said sheet engaging portion in a gripping action, spring means for actuating the movable jaw into gripping engagement with the sheet engaging portion of the fixed jaw, and means for opening the jaws.

70 21. In a sheet gripping device of the character described, a supporting bar, hingedly connected complementary movable and stationary jaws

forming a loop encircling the supporting bar, the stationary jaw being in the form of an arcuate metal band directly engaging the exterior of the supporting bar with one end bent outwardly to provide a sheet engaging surface spaced from the 5 supporting bar, means hingedly connecting the opposite end portion of the stationary jaw with the movable jaw intermediate the ends of the movable jaw, one end of the movable jaw being engageable with the sheet engaging portion of the stationary jaw, spring means confined between the opposite end of the movable jaw and the adjacent portion of the stationary jaw to yieldingly hold the jaws closed, and means for 10 opening the jaws.

15 22. In a sheet gripping device of the character described, a supporting tube, means fixed to the supporting tube and providing a sheet engaging surface spaced from the outside surface of the tube, a movable jaw, means pivotally mounting 20 the movable jaw from the supporting tube so that a free end of the movable jaw is engageable with said sheet engaging portion, spring means to urge the movable jaw into gripping engagement with said sheet engaging portion, and means within 25 the supporting tube and having a connection with the movable jaw for actuating the same to disengage its free end from said sheet engaging portion.

30 23. In a sheet gripping device of the character described, a supporting tube, a metal band fixed to the outside of the supporting tube and having an end portion bent to provide a sheet engaging surface spaced from the exterior of the tube, a movable jaw, means pivotally mounting the movable jaw from the supporting tube at a distance arcuately spaced from the said sheet engaging portion and with the free end of the movable jaw arranged for engagement with said sheet 35 engaging portion, spring means to yieldingly urge the movable jaw into gripping engagement with said sheet engaging portion, an arm carried by the movable jaw and extending through an opening in the supporting tube into the interior thereof, and actuating means rotatable within the supporting tube and connected with said arm to move the jaw in opposition to said spring means for disengaging the same from the sheet engaging portion.

40 24. In a sheet gripping device of the character described, a supporting tube, a stationary jaw fixed to the exterior of the supporting tube and having a sheet engaging portion spaced outwardly from the exterior of the tube, a stop also fixed to the tube and disposed adjacent said sheet engaging portion of the stationary jaw against which a sheet abuts to be properly located with respect to said sheet engaging portion, a movable jaw, means pivotally mounting the movable jaw from the supporting tube in such position that a free end portion of the movable jaw is engageable with the sheet engaging portion of the stationary jaw in a gripping action, spring means to urge the movable jaw into gripping engagement with the sheet engaging portion of the stationary jaw, an arm on the movable jaw extending into the interior of the tube, and actuating means rotatable within the tube and engaged with said arm for disengaging the movable jaw from the sheet engaging portion of the stationary jaw.
